United States Patent Office.

W. E. CAMERON, OF GREEN ISLAND, NEW YORK.

Letters Patent No. 78,259, dated May 26, 1863.

IMPROVED FOLDING STOOL.

The Schedule referred to in these Letters Patent and making part of the same.

TO ALL WHOM IT MAY CONCERN:

Be it known that I, W. E. CAMERON, of Green Island, in the county of Albany, and State of New York, have invented a new and improved Folding Stool; and I do hereby declare that the following is a full, clear, and exact description thereof, which will enable others skilled in the art to make and use the same, reference being had to the accompanying drawings, forming part of this specification, in which—

Figure 1 is a side view of my improved stool open, one of the upper arms and part of the seat being broken away to show the construction.

Figure 2 is a sectional view of the same closed, one of the upper and one of the lower arms being cut away.

Similar letters of reference indicate corresponding parts.

My invention has for its object to furnish an improved folding portable stool, so constructed and arranged that it may be folded into a very neat and compact form for storage or transportation; and it consists in the construction and combination of the various parts, as hereinafter more fully described.

A is the central bed-plate or pivoting-block of the stool. B are the lower arms of the stool, which, when turned down, form the feet. The ends of the arms B are pivoted to ears a^1 , formed upon the four sides of the bed-plate or block A, in such a way that they may be turned down, as shown in fig. 1, and turned or folded up, as shown in fig. 2. When turned down or opened to form a seat, the arms B are connected to each other, and at the same time braced by the hook-bars C, one end of which is pivoted to one of the arms B, and the other end has a hook formed upon it, which hooks into an eye attached to another of said arms, as shown in fig. 1. When the arms B are folded up to close the stool, the brace-rods C are secured along the sides of the said arms B, as shown in fig. 2, so as to be entirely out of the way. D are the upper arms, the lower ends of which are pivoted to ears a^2 , formed upon the upper side of the plate or block A, above and within the ears a^1 , so that the arms D and B, when folded up, may stand parallel with each other, as shown in fig. 2. Upon the upper ends of the arms D are formed or to them are attached hooks or knobs E, which pass through holes in the corners of the cloth F, which forms the seat of the stool. To the centre of the upper side of plate or block A, is rigidly attached a vertical standard, G, to the upper end of which are pivoted the inner ends of the brace-bars H; the outer ends of which are so formed as to enter the sockets I, formed in or attached to the arms D, to support the said arms against the tendency to be drawn in by pressure upon the seat F. When the stool is folded up, the braces H hang along the sides of the standard G, as shown in fig. 2. When the stool is folded up for storage or transportation, the seat-cloth F is wrapped around the folded stool, and secured in place by buttons attached to said cloth near one edge, as shown in fig. 2.

Having thus described my invention, what I claim as new, and desire to secure by Letters Patent, is—

The plate A, constructed as described, and provided with the ears a^1 a^2 to receive the arms B D, whereby the arms B are adapted to be folded up beside the arms D, when the latter are folded, substantially as described for the purpose specified.

W. E. CAMERON.
